Frame B is octagon in shape, and is provided with suitable spaces, a, 25 divided from each other by ornamentations b, and each adapted to contain suitable lettering, as shown. Beneath the frame B is the representation of a pair of spectacles, C, the frames c of which are octagon in shape. Upon 30 the upper edge of frame B there is an ornamental piece, D, protruding upwardly from which are a stem, D', and a ring, E, also octagon in form. The dial or face is convex in shape.

What I claim is—

1. The design for signs described, consisting of the representation of a time-piece face or dial surrounded by an octagon frame divided into plain and ornamental spaces, as shown. 35
